UNITED STATES PATENT OFFICE.

CHARLES KEMP, OF NEW YORK, N. Y.

LOCK.

1,305,469.

Specification of Letters Patent. Patented June 3, 1919.

Application filed March 11, 1919. Serial No. 281,931.

To all whom it may concern:

Be it known that I, CHARLES KEMP, a citizen of the United States, and a resident of the borough of Manhattan, city, county, 5 and State of New York, have invented certain new and useful Improvements in Locks, of which the following is a specification.

My improvements relate to the type of lock designated in my concurrent applications Serial No. 258,701, filed Oct. 18, 1918, 10 and Serial No. 265,857, filed Dec. 9, 1918, in which a rotatable hasp cylinder is adapted for engagement with a jamb staple or equivalent stationary securing part,—the 15 object of the present invention being the production of a lock of this character of simplified structure and few parts, but of maximum strength and security. Hence, the invention consists in the specific construction, combination and arrangement of 20 parts described and claimed, distinctive features being the provision of a duplex hasp cylinder for engagement with two separate jamb staples; the peculiar formation of the 25 rack bolt, its spring pawl, etc., and other details hereinafter set forth.

In the accompanying drawings,

Figure 1, is a section of my improved lock, 30 taken upon plane of line 1—1, Fig. 2;
Fig. 2, is a section of the same, taken upon plane of line 2—2, Fig. 1;

Fig. 3, is a view similar to Fig. 2, broken away in part, showing the rack bolt in retracted position;

Fig. 4, is a side elevation of the staple plate;

Fig. 5, is an end view thereof;

Fig. 6, is a side view of the rack bolt pawl;

Fig. 7, is an edge view thereof;

Fig. 8, is a sectional elevation taken upon plane of line 8—8, Fig. 2;

Fig. 9, is an elevation of the inner side of the base plate;

Fig. 10, is an edge view thereof, with the posts partly broken off;

Fig. 11, is an elevation of the reverse side of the rack bolt;

Fig. 12, is a sectional detail showing one 50 of the trunnions for the hasp cylinder;

Fig. 13 is an elevation of the hasp cylinder;

Fig. 14, is an end view thereof; and

Fig. 15, is a transverse section thereof, 55 taken upon plane of line 15—15, Fig. 12.

Fig. 16, is a sectional detail of the rear portion of the rack bolt.

The casing for the operative parts consists of the base plate B, which is screwed to the door D, or other closure to be protected, and the cover C, which is screwed to the base plate B, after the latter is secured to the door D. b, b, Fig. 9, represent the holes in the base plate B, for the screws by which it is secured to the door D; and 60 b', b', the female threaded posts which receive the screws by which the cover C, is secured to said base plate B.

The cover C, is formed with the semi-cylindrical recess c, for the accommodation of 70 the hasp cylinder H, the ends of which latter are formed each with a radial recess h, (Fig. 14) for engagement with the trunnion bosses c', (Figs. 2 and 12) on the cover C.

The hasp cylinder H, is essentially hollow in that it is formed with longitudinal recesses h', h', and lateral slots h², h², h², h², opening thereinto for the accommodation of the arms s, s, s, s, and cross bars s', s', of 80 the staples S', S', as will be seen more particularly by reference to Figs. 1, 2 and 8.

The staples S', S', are protuberant from an angular base plate S, which is secured to and countersunk in the jamb J, of the door frame or the like, as indicated in Figs. 1 and 8,—the lock, as before intimated, being secured by the base plate B, to the door or other closure D, and it is secured thereto in such manner that the end of the casing in which the hasp cylinder is mounted will 90 overlap the staples S', S', and their base plate S, when the door or other closure is turned to closed position. The edge b², of the base plate B, at this end of the lock terminates short of the edge c', of the cover C, 95 so as to leave an opening in the lock casing through which the staples S', S', may project when the hasp cylinder H, is in proper position to receive said staples.

It is to be noted in this connection that 100 my present form of hasp cylinder H, is practically a duplication of that shown in my hereinbefore mentioned concurrent applications, the essential difference resting in the fact that it is duplex in function, in 105 that it is made to accommodate and engage with twin staples S', S', in lieu of the single staple heretofore shown and used.

The peripheral surface of the medial portion h³, of the hasp cylinder H, between the 110

openings h' , h' , and adjacent lateral slots h^2 , h^2 , is formed with gear teeth h^4 , for engagement with rack teeth r , formed for the purpose on the outer end r' , of the rack bolt 5 R. The rear portion of said rack bolt R, is formed with lateral bearing arms r^2 , r^2 , r^2 , r^2 , which rest against the inner side walls of the cover C, as shown particularly in Figs. 2 and 3. These four slidable bearings r^2 , r^2 , 10 r^2 , r^2 , effectually centralize and support the rack bolt R, in any and all positions, so that I am enabled to dispense with the casting guide posts, supports etc., used for the purpose in my aforesaid concurrent applications, thereby simplifying and lightening the structure considered as a whole.

Said rear portion of the rack bolt R, is also slotted to straddle the inner end of the latch spindle L, as shown in Fig. 1. The 20 key arbor K, and the latch spindle L, are positioned in axial alinement, but are not connected with each other in any manner, the latch spindle L, being journaled on the body plate of the cover C, while the key 25 arbor K, is journaled on the base plate B, as shown more particularly in Fig. 1, of the drawings.

Pivotedly supported on a trunnion r^3 , on the face of the rack bolt R, next the base 30 plate B, is a spring pawl P, formed with a lateral bearing extension or tongue p , shown particularly in Figs. 1 and 7, which protrudes into and through a recess r^4 , formed for it in the rack bolt R, and into 35 the path of action of the bolt actuating cam arms k , l , of the key arbor K, and of the latch spindle L. In the said recess r^4 , is positioned a coiled spring r^5 , interposed between the bottom of the recess r^4 , and the 40 under side of the tongue p , of the pawl P, and tending constantly to thrust said tongue p , into the path of the actuating cam arms k , and l , of the key arbor K, and of the latch spindle L. A stud r^6 , on the bottom 45 of the recess r^4 , and a corresponding stud p' , on the under side of the pawl tongue p , may be provided for the purpose of retaining the spring r^5 , in position. The long arm of the pawl lever P, is formed with a shoulder r^2 for engagement with a stationary 50 part or stop s^x , on the cover C, when the rack bolt R, is advanced, as in Fig. 2, thereby preventing the retractile movement of said rack bolt R, until said pawl shoulder 55 p^2 , is released from the stop s^x —this release being effected by the depression of the pawl tongue p , into the recess r^4 , by either of the actuating cam arms k , or l . The stop s^x , also, in conjunction with the pawl shoulder 60 p^2 , prevents the forward travel of the rack bolt R, when the latter is in retracted position, as in Fig. 3, until cleared by the rocking of the pawl P, by means of one of the actuating cam arms k , and l .

65 Adjacent to the mouth of the recess r^4 ,

the rack bolt is formed on each side with lateral extensions r^6 , r^6 , to afford ample contactual surfaces for engagement with the actuating cam arms k , l . This construction will be understood by reference particularly 70 to Fig. 16, when considered with Figs. 1, 2, 3 and 8.

When either of the bolt-actuating cam arms k , or l , are turned in the right direction out of normal position, they not only 75 rock the pawl P, by depressing its tongue p , against the resistance of the spring r^5 , thereby releasing the shoulder p^2 , from the stop s^x , but they also enter the mouth of said recess r^4 , so that continued movement of the 80 arm (k or l) by reason of the engagement of its free end with the side walls of the recess r^4 , throws the rack bolt R, backward or forward causing it to rotate the hasp cylinder H, to release or secure the staples S', S', as 85 the case may be.

T, represents a key escutcheon and tumbler case of the well known cylinder or pin type, the tongue of which engages with the slot h' , in the key arbor K, to actuate the latter in a manner well known in the art. l^2 , is a spring bearing upon the eccentric portion l^3 of the latch spindle and tending to hold the spindle as set by means of the latch handle l^1 , also in a manner well known in 95 the art.

As before intimated, although the latch spindle and the key arbor are in axial alinement they are independently rotatable upon their axes. Hence either may be used to 100 reciprocate the rack bolt B, to make or break connection between the hasp cylinder H, and bolt B, and the staple S.

By placing the spring r^5 , within the recess r^4 , in the rack bolt R, I isolate and protect it and attain more direct action against the bearing tongue p , of the pawl P. Furthermore by this self-contained structure and housing of the spring I obviate all danger of its displacement within the lock; and 110 by placing the fulcrum r^3 , adjacent to the bearing tongue p , a slight depression of the latter is sufficient to release the shoulder p^2 , on the long arm of the pawl P, from the stop s^x , so that quick release of the bolt R, is 115 assured in either direction.

By the use of twin staples S', S', in conjunction with my duplex hasp cylinder H, I attain great strength and security with simplicity of parts and structure; and all the 120 operative parts of my locking mechanism are inclosed and rendered inaccessible when connection is made with the twin staples, so that I attain a lock that it is difficult if not impossible to "jimmy" or otherwise tamper 125 with.

What I claim as my invention and desire to secure by Letters Patent is:

1. In closure means of the character designated, in combination with twin staples, a 130

lock comprising a rotatable hasp cylinder adapted to engage with both of said staples and formed with peripheral teeth, a rack bolt formed with teeth engaging said hasp cylinder teeth, a spring pawl pivotally mounted on said rack bolt and formed with a shoulder for engagement with a stationary part and adapted for engagement with actuating cam arms on the key arbor and on the latch spindle, together with said cam-armed key arbor and said cam-armed latch spindle, for the purpose described.

2. In closure means of the character designated, in combination with a jamb staple, a lock comprising a rotatable hasp cylinder adapted to engage said staple and formed with peripheral teeth, a rack bolt formed with teeth engaging said hasp cylinder teeth and with a recess the side walls of which are

adapted to receive and engage with the free ends of actuating cam arms on the key arbor and on the latch-spindle, said cam-armed key arbor and latch spindle, a pawl pivotally mounted on said rack bolt and formed with a shoulder for engagement with a stationary part and also formed with a laterally extending bearing tongue protruding into and through the said recess in the rack bolt, said stationary part and a coiled spring interposed in said recess between the bottom thereof and the under side of said lateral bearing tongue on the pawl, for the purpose described.

CHARLES KEMP.
